UNITED STATES PATENT OFFICE

JOSEF FELDMAYER, OF MUNICH, GERMANY

PERMUTATION LOCK

Application filed May 12, 1928, Serial No. 277,331, and in Germany July 29, 1927.

This invention relates to a permutation-lock with locking-bodies adapted to be inserted and adjusted and designed to lock the latch, as described in my patent application Serial Number 231,647, dated November 7th, 1927. The invention consists in a circular arrangement of the locking bodies and of the co-operating elements.

An embodiment of the invention is illustrated, by way of example, in the accompanying drawing in which:

Fig. 1 is a front-elevation showing the improved permutation-lock.

Fig. 2 is a longitudinal section on line 2—2 of Fig. 1.

Fig. 3 is a front-elevation showing the permutation-lock from which the locking bodies and their bearing ring have been removed.

Fig. 4 is a cross section on line 4—4 of Fig. 3.

Fig. 5 shows in elevation the bearing ring with the locking bodies removed from the lock.

Fig. 6 is a cross-section of Fig. 5.
25 Fig. 7 is a similar view as Fig. 3 showing a modified construction of the permutation lock, the locking bodies and their bearing ring being removed.

Fig. 8 is a side-elevation of Fig. 7.

The locking bodies 1 are of a similar construction as the locking-bodies described in my parent application Serial Number 231,647. Each locking body consists of a circular disc-shaped element having a notch 2 in its periphery, a handle and a short axle 3 in the centre of this disc-shaped element. Each locking body has further two indentations 4 arranged symmetrically the one opposite the other and with which engages a plate-spring to securely hold the locking body in its actual position so that the handle is standing perpendicularly to the bearing surface. The locking bodies can be turned towards both sides from this position, whereby different combinations of adjustments can be produced. In some locking bodies the notch 2 is symmetrical to the handle and in other locking bodies it is unsymmetrical so that for each locking body a certain adjusted position is necessary in order that a locking element can be moved

which intersects the surfaces and notches of the locking bodies, the bolt being released by this movement.

For the circular arrangement of the locking bodies a circular bearing ring 5 for the same and a ring-shaped locking element are used, the unlocking being effected by a part-rotation of the locking ring. The bearing ring 5 has in its upper surface an annular groove 6 and as many radial slots 7 as there are locking bodies. The discs of the locking bodies fit accurately into these slots and their axles 3 are then accommodated in the annular groove 6 of the bearing ring 5.

In a central cavity of the bearing ring a 65 cup-shaped spring-plate 8 is located which has resilient tongues pressing each against the inner portion of the disc of a locking body, as shown in Figs. 5 and 6.

In the lower surface of the bearing ring 70 an annular groove 9 is arranged which is so deep that it intersects the slots 7 in the upper surface of the bearing ring, and the discs of the locking bodies engage also with this lower groove and intersect the same. Into 75 this annular groove 9 a cylindrical locking ring 10 is inserted so that it can rotate in the same. This locking ring 10 has as many recesses 11 in its upper edge as there are locking bodies, said recesses being of such 80 dimensions that the portions of the discs of the locking bodies which intersect the annular groove 9 and the locking ring 10 of the same fit into these recesses, the locking ring 85 impeding not the insertion and adjusting of the locking bodies but being incapable of rotary movement unless all the locking bodies are adjusted so that their notches are situated in their annular groove 9.

The bearing ring 5 is fixed on the rear- 90 plate 12 of the lock casing, the locking ring 10 being rotatable between said plate and ring. The locking ring 10 has a laterally projecting tongue 13 engaging with a bolt 14, the latter being forced by the action of a 95 spring 15 into the locking position together with a locking element 16 of the lock. This locking element 16 may consist of a shackle, adapted to be engaged with the bolt in opposition to the action of a spring 17, as in 100

padlocks, or of a pin 18 having a transverse groove as shown in Fig. 8, designed for satchels.

When the corresponding end of the shackle 16 or of the pin 18 is pressed in, the bolt 14 or 14' is pushed back in opposition to the action of spring 15 or 15' and engages with the incision of the shackle 16 or pin 18.

The lock casing has a hole 19 (Fig. 7) into which the pin 18 is to be inserted and the bolt 14' has an extension 20 with bevelled friction-surface 21 situated under the hole 16.

The shackle 16 or the locking pin 18 can be inserted at any time independently of the adjusting of the locking bodies, so that the lock can be locked at any time. For unlocking the bolt the locking ring 10 is employed, the tongue 13 of which pushes the bolt back on a slight rotation of the locking ring to the right and releases the shackle or other locking element.

For rotating the locking ring a ring 23 having two knobs 24 serving as handles is loosely mounted in the cover-plate of the lock. This ring 23 has a cylindrical extension 25.

To the rear plate 12 of the lock-casing a plate 26 is connected on which the locking ring is loosely mounted. An extension 25 from the ring 23 has two teeth 27 engaging with a cut-out portion 28 of the plate 26 and extending to the rear-plate 12 of the casing so that they bear against opposite sides of the tongue 13 of the locking ring, said tongue being situated also in the cut out portion 28 of the bottom-plate. The side walls of this cut-out portion 28 form also stops for the tongue 13 to limit the rotation of the locking ring in both directions. When the tongue is bearing against the left side wall of the portion 28, it is secured in this position by the bolt 14 and by the spring of said bolt, and in this position all the recesses 11 of the locking ring register with the notches 7 of the bearing ring so that the locking bodies can be inserted or adjusted.

When a locking body is adjusted so that its notch 2 does not register with the lower annular groove 9 of the bearing ring, the disc of the locking body intersecting this annular groove, it is not possible to rotate the ring 23 so that the lock cannot be unlocked.

The unsymmetrical arrangement of the notch 2 in some locking bodies is made for the purpose that, even if all locking bodies have been adjusted to the same position, it is not possible to unlock the lock.

The locking bodies in which the notch is unsymmetrical to the handle or the axle must adopt, for opening the lock, another position than the other locking bodies. The locking bodies can be interchanged at will to obtain other adjusting combinations.

In the form of construction shown in Fig. 65 1 three symmetrical and three unsymmetrical

locking bodies are provided, and the three unsymmetrical bodies 1' are mounted in the lower portion of the lock and must all three be turned in an outward direction in order that the lock may be unlocked, while the other three locking bodies must be placed in the middle position.

Upon the adjusting of the lock all six locking bodies are preferably turned in an outward direction or brought into the middle-position, as shown in Fig. 6. It is however sufficient to bring any one of the locking bodies into another position as shown in Fig. 1.

If the three unsymmetrical locking bodies 1' were removed and turned upside down they would, in order to bring the lock into the open position, have to be turned in inward direction instead of in outward direction, as they would then, in this position, 85 intersect the annular groove 9 with their notches 2 and let the locking ring pass.

The locking bodies are held in their bearings by a cover-plate 29. This cover-plate has radial slots 30 which are placed over the locking bodies so that these locking bodies project through the slots, the axles of the locking bodies being pressed by the cover-plate into the annular groove 6 of the bearing ring 5.

The cover-plate 29 has at its centre an inwardly extending bolt 31 with a narrowed portion 32. The end of bolt 31 engages with the hole 40 of the rear-plate 12 of the lock-casing so that the narrowed portion 32 is 100 situated in the plane of plate 26.

The plate 26 has a cut out portion 33 in which a slide 34 is located which projects from one side of the lock-casing. This slide 34 has a hole 35 with slot 35'. The hole 35 is of the same diameter as the bolt 31 the width of the slot 35' corresponding to the narrowed portion 32 of the bolt.

If the slide is not completely inserted into the lock-casing so that the hole 35 registers with the hole 40 in the rear-wall of the lock-casing, the bolt 31 can be inserted. When then the slide is completely pushed in, its slot 35' engages over the narrowed portion 32 of the bolt and securely holds the same in this position.

The cylindrical extension 25 of the ring 23 has an extension 36, and in the slide 34 an arc-shaped slot 37 is arranged with which this extension 36 engages and prevents pulling out of the slide.

When the lock is adjusted for the unlocked position and unlocked by a rotation of the ring 23, the extension 36 of this ring disengages from the slot 37 of the slide so that the slide can be pulled out.

Between the cover-plate 29 and the bottom of the bearing ring 5 a spiral spring 38 is inserted which lifts the cover-plate 29 with its bolt 31 as soon as the slide is pulled out 130

so that its hole 35 comes to register with the bolt.

On the outer surface of the cover-plate 29 a knob 39 is provided to facilitate the pressing in of the cover-plate.

5 I claim:—

1. A lock, comprising in combination a number of disc-shaped rotatable locking bodies arranged in a circle and having each a notch in its periphery, a handle on each locking body, a bearing ring in which said locking bodies are journaled, means for securely holding said locking bodies in said bearing ring, and a locking ring engaging with said bearing ring and intersecting the notches of said locking bodies and adapted to be rotated if all the locking bodies are correctly adjusted.

2. A lock, comprising in combination a number of disc-shaped rotatable locking bodies arranged in a circle and having each a notch in its periphery, the notch in some locking bodies being arranged differently from the notch in other locking bodies, a handle on each locking body, a bearing ring in which said locking bodies are inserted, means for securely holding said locking bodies in said bearing ring, and a locking ring engaging with said bearing ring and intersecting the notches of said locking bodies and adapted to be rotated if all the locking bodies are correctly adjusted.

3. In a permutation lock, a casing, a plurality of disk-shaped locking bodies arranged in a circle and rotatably mounted in said casing, each body having a notch in its periphery and a handle for rotatably adjusting it, and a locking ring intersecting the notches of said rotary bodies and adapted to be rotated if all the locking bodies are correctly adjusted.

4. In a permutation lock, a casing, a plurality of disk-shaped locking bodies arranged in a circle and rotatably mounted in said casing, each body having a notch in its periphery and a handle for rotatably adjusting it, and a locking ring having ribs for engagement with the notches of the bodies to permit rotation of said ring when said bodies are correctly adjusted and recesses alternating with said ribs and adapted to receive the bodies to permit rotary motion of the latter.

5. In a permutation lock, a casing, a bearing ring in said casing, a plurality of disk-shaped locking bodies arranged at spaced intervals around said ring and rotatably mounted thereon, each body having a notch in its periphery and a handle for rotatably adjusting it, and a locking ring movable about said bearing ring and intersecting the notches of said rotary bodies and adapted to be rotated if all the locking bodies are correctly adjusted.

6. In a permutation lock, a casing, a plurality of disk-shaped locking bodies ar-

ranged in a circle and rotatably mounted in said casing, each body having a notch in its periphery and a handle for rotatably adjusting it, means for holding said bodies in position and releasing the same to permit independent application and removal of the bodies, and a locking ring intersecting the notches of said rotary bodies and adapted to be rotated if all the locking bodies are correctly adjusted.

7. In a permutation lock, a casing, a bearing ring in said casing provided with open bearings, a plurality of disk-shaped locking bodies arranged at spaced intervals about said ring and removably journaled in said open bearings, a removable holding member for retaining said bodies in said bearings, and a locking ring intersecting the notches of said rotary bodies and adapted to be rotated if all the locking bodies are correctly adjusted.

In testimony whereof I affix my signature.

JOSEF FELDMAYER.
